UNITED STATES PATENT OFFICE.

SAMUEL ELDER, OF WASHINGTON, DISTRICT OF COLUMBIA, ASSIGNOR TO MIEHLE PRINTING PRESS & MANUFACTURING COMPANY, OF CHICAGO, ILLINOIS, A CORPORATION OF ILLINOIS.

GUIDE MECHANISM.

Application filed August 27, 1923. Serial No. 659,494.

To all whom it may concern:

Be it known that I, SAMUEL ELDER, a citizen of the United States, residing at Washington, in the District of Columbia, have invented certain new and useful Improvements in Guide Mechanism, of which the following is a specification.

This invention relates to a new and improved guide mechanism and more particularly to mechanism adapted to guide the travel of the boards or plate carrying members in engraving presses or similar apparatus.

In certain types of presses particularly adapted for use in producing engraved notes, bonds, and the like, the engraved plates are carried by boards which travel about the surface or bed of a supporting table. These boards are moved by a draft chain to which they are connected and usually follow an approximately rectangular path. During the straight runs the boards are guided upon both sides and a smooth movement is assured. As the boards make the turns, however, it has been found that there is a tendency for angular displacement of the boards and also a tendency to enter the straight guides with a heavy shock or blow.

It is an object of the present invention to provide guide means upon the table and associated boards adapted to guide and control the boards at the points in their travel where they change direction.

It is a further object to provide a construction of this character which is simple in design and which may be applied to existing structures without material alteration therein.

Other and further objects will appear as the description proceeds.

In the embodiment shown herein for purposes of illustration, the guide means takes the form of spring pressed plungers carried by the table and co-operating guideways formed upon the lower surface of the boards.

I have illustrated a preferred embodiment of my invention in the accompanying drawings, in which—

Figure 1 is a plan view of a press table with the plate carrying boards and associated parts, the upper press mechanism being removed for the sake of clearness;

Figure 2 is a view showing a board as seen from below;

Figure 3 is an elevation of the board; Figure 4 is a section taken on line 4—4 of Figure 2; and

Figure 5 is an enlarged sectional detail taken on line 5—5 of Figure 1, showing the guide plunger construction.

Referring now to Figure 1, the table 6 is provided with the draft chain 7 carried in the bed of the table. This chain travels in an approximately rectangular path passing about the driving sprockets 8 and the idler sprockets 9. The sprockets 8 are driven by means of the gear wheels 10 carried upon the same shafts which gear wheels mesh with the main gear 11.

The chain 7 is provided with the spaced draft pins 12, each of which enters a bearing 13 in the lower side of a plate-carrying board 14. This connection permits the board to pivot about the draft pin. During the straight runs of the boards 14, they are guided between the inner guides 15 and outer guides 16. As shown in Figure 1, the boards when making their change of direction are out of engagement with either of these guides and are also out of engagement with the curved connection portions 17 and 18 of the guide surfaces. The present invention provides means for guiding the boards during this portion of its travel.

The normal direction of movement of the boards is counterclockwise as seen in Figure 1. The table is provided with four guide plungers 19, one of which is shown in detail in Figure 5. This plunger 19 is fitted into a bore 20 in the table member 21. The reduced lower portion 22 of the plunger is surrounded by the spring 23 which tends to thrust the plunger upwardly. The plunger is retained in place by the threaded collar 24 against which the flange 25 of the plunger bears. Co-operating with these plungers are the guide channels 26 and depressing guides 27 formed in the plates 28 secured to the corners of the inner face of the boards 14.

In the operation of the press, as the forward edge of a board approaches the end of each straight run, a depressing guide 27 engages the corresponding guide plunger 19 and depresses that plunger so that it bears against the under surface of the board as the board continues to travel. As this travel is continued, the plunger head reaches the entering portion 29 of the aligned guide

channel 26 and the plunger spring presses it upwardly into this recess. By aligned guide channel is meant the guide channel upon the opposite edge to the depressing 5 guide, the depressing guide being upon the front edge and the guide channel adjacent the rear edge of the board. The engagement of this pin with the channel and the engagement of the draft pin with the board 10 together define two points limiting and controlling the movement of the board and it is guided as it makes its change of direction. It is also caused to enter evenly and without undue jar between the succeeding guide- 15 ways 15 and 16. Immediately after the forward end of the board has entered these guideways, the rear end clears the plunger 19 which remains in position to guide the succeeding board. It will be noted that the 20 recesses 27 are curved upon an arc corresponding to that made by the sprocket chain 7 about the sprocket wheels 8 and 9. This curve is necessary since the planks move upon that curve during their change of direction. 25

As during the course of a single trip around the table, the four edges of the board are in turn the front or leading edge, it is necessary to provide all four corners of 30 the board with identical recesses 26 and 27. The various boards are, of course, identical.

While this guide mechanism has been described particularly in connection with its application to an engraving press, it may 35 obviously be applied to other constructions involving the continuous movement of boards or similar members. It is my intention to cover all such modifications as come within the scope of the appended claims.

40 I claim:

1. A movable member, guide grooves formed in said member, supporting means for said member, means adapted to move said member through a closed path, and 45 guide members carried by the supporting means adapted to coact with the guide grooves in said movable member to guide it during change of direction of movement.

2. In a printing press, a movable plate 50 carrying member, a press table having a bed therein, means for moving said plate carrying member through a closed path upon the bed of the press, guide members extending from the press bed, and guide channels 55 formed in the plate carrying member adapted to coact with the guide members to guide the plate carrying member during change of direction of movement.

3. In a printing press, a movable plate 60 carrying member, a press table having a bed therein, means for moving said plate carrying member through a closed path upon the bed of the press, guide members extending from the press bed, depressing guides and 65 guide channels formed in the plate carrying

member adapted to depress and to coact with the guide members to guide the plate carrying member during change of direction of movement.

4. In a printing press, a movable plate 70 carrying member, a press table having a bed therein, means for moving said plate carrying member through a closed path upon the bed of the press, spring pressed guide plungers extending upwardly from the press bed and guide channels formed in the under side of the plate carrying member adapted to coact with the guide members to guide the plate carrying member during change of direction of movement. 75

5. In a printing press, a movable plate 80 carrying member, a press table having a bed therein, means for moving said plate carrying member through a closed path upon the bed of the press, spring pressed guide plungers extending upwardly from the press bed and depressing guides and 85 guide channels formed in the under side of the plate carrying member adapted to depress and to coact with the guide members to guide the plate carrying member during change of direction of movement. 90

6. In a printing press, a movable plate 95 carrying member, a press table having a bed therein, means for moving said plate carrying member through a closed path upon the bed of the press, a plurality of guide members, one located adjacent each point of change of direction of the plate carrying member, and guide means upon the member and adapted to co-operate with the guide members. 100

7. In a printing press, a movable plate 105 carrying member, a press table having a bed therein, means for moving said plate carrying member through a closed path upon the bed of the press, a plurality of guide members, one located adjacent each point of change of direction of the plate carrying member, and guide channels formed in the 110 under face of the plate carrying member and adapted to co-operate with the guide members during change of direction of movement. 115

8. In a printing press, a movable plate 120 carrying member, a press table having a bed therein, means for moving said plate carrying member through a closed path upon the bed of the press, a plurality of guide members, one located adjacent each point of change of direction of the plate carrying member, and depressing guides and guide channels formed in the under face of the 125 plate carrying members and adapted to depress and to co-operate with the guide members during change of direction of movement.

9. In a printing press, a movable plate 130 carrying member, a press table having a bed therein, means for moving said plate carry-

ing member through a closed path upon the bed of the press, a plurality of guide members, one located adjacent each point of change of direction of the plate carrying member, a depressing guide in each edge of the plate carrying member and a guide channel having its entering portion aligned with each depressing guide, said guide channel being adapted to co-operate with the 10 guide members to guide the plate carrying member during change of direction of movement.

10. In a printing press, a movable plate carrying member, a press table having a bed 15 therein, means for moving said plate carrying member through a closed path upon the bed of the press, a plurality of spring

pressed guide plungers extending upwardly from the press bed, one of said plungers being located adjacent each point of change 20 of direction of the plate carrying member, a depressing guide in each edge of the plate carrying member adapted to depress the plungers to permit the member to pass over them, and a curved guide channel in the 25 lower face of the member having its entering portion aligned with each depressing guide, said guide channels being adapted to coact with the plungers to guide the plate carrying member during change of direction 30 of movement.

Signed at Washington, D. C., this 23rd day of August, 1923.

SAMUEL ELDER.
